UNITED STATES PATENT OFFICE.

FOLKE JARL ANDERS WENNERGREN AND FRIDTJOF ANDERSEN, OF TROLLHATTAN, SWEDEN, ASSIGNORS, BY MESNE ASSIGNMENTS, TO TROLLHÄTTANS ELEKTRO-THERMISKA AKTIEBOLAG, OF STOCKHOLM, SWEDEN.

APPARATUS FOR PRODUCING ZINC POWDER.

Application filed October 6, 1922. Serial No. 592,821.

To all whom it may concern:

Be it known that we, FOLKE JARL ANDERS WENNERGREN and FRIDTJOF ANDERSEN, subjects of the King of Sweden, and residing at Trollhattan, Sweden, have invented certain new and useful Improvements in Apparatus for Producing Zinc Powder, of which the following is a specification.

This invention relates to improvements 10 in apparatus for producing metallic powder from certain metal vapors, such as zinc, lead, cadmium, aluminium and the like.

The apparatus is shown in the accompanying drawings in which:

15 Figure 1 is a longitudinal view partly in section of the improved apparatus.

Figs. 2, 3 and 4 are sectional views of modified forms of powder discharging devices forming part of the apparatus.

20 Referring to Fig. 1, A indicates an electrical reduction furnace; A' and A² the electrodes of the same; B a pipe for conveying metal vapors and non-condensable gases from the furnace; C a cooling condenser, in which the metal vapors from the reduction furnace are subjected to intense cooling to convert the same into metal powder.

D is a cooled receiver into which the 30 powder falls from the container C. H designates a discharge pipe for conveying non-condensable gases from the receiver. Said pipe H discharges into a fluid seal, (not shown). The apparatus is maintained in a 35 known manner under a predetermined suitable pressure.

A conveyer E is arranged in the receiver D and functions to continuously convey the powder to the outlet end of the receiver.

40 It has been found from experience, that if said powder is pressed toward a vertical or nearly vertical surface, without having an opportunity to escape easily from the receiver, the powder will assume a more or less 45 solid consistency, and finally the powder will be compact and will fill the whole receiver D, so that the working of the conveyer will cease. According to the invention, this inconvenience is eliminated by causing 50 the powder to change its direction of movement, and to accumulate at the outlet to such a height, that leakage of the gases is prevented.

For this purpose, the outer end of the re-

ceiver opens into a lateral receiver G, and the threads E' of the conveyer E are pitched in an opposite direction at the outer end of the receiver to that of the pitch of the thread of the remaining portion of the conveyer. Owing to this construction, powder 60 is forced through the receiver D and upward into the outer receiver G to a certain height, so that the accumulated body of powder prevents the non-condensable gas 65 from leaking out through the receiver G.

The receiver D is cooled by introducing a cooling medium at D' and discharging this medium at D². In a similar manner the outlet receiver G is cooled by introducing a cooling medium at G' and discharging the 70 same at G². The ends of the receiver D in which the shaft of the conveyer is journaled, are cooled at O, O', O² and O³.

Referring to Fig. 2, F is a bucket wheel, by means of which the powder is forced into 75 the conduit. Said wheel is preferably provided with radially arranged blades and is situated opposite to the inlet end or mouth J of the conduit G. E' indicates the threads of the conveyer.

In the embodiment shown in Fig. 3, the conduit G is arranged at the extreme end of the receiver D, and the bucket wheel K has an end flange K'.

In the form shown in Fig. 4, the conduit 85 G extends longitudinally of the receiver and forms an elbow, so that the powder transported in the receiver D is pressed toward the oblique surface L of the outlet receiver G and is caused to rise to a certain height 90 in said receiver before leaving the outlet at M.

The height, to which the powder is accumulated in the outlet receiver or conduit 95 G for establishing a seal, is dependent upon the pressure of the gas or gases in the apparatus.

From the foregoing, it is believed that the construction, operation and advantages of the invention may be readily understood and it is apparent that changes may be made in the details disclosed without departing from the spirit of the invention as expressed in the claims.

What is claimed and desired to be secured by Letters-Patent is:

1. The combination with a furnace for 100 producing metal vapors mixed with non

condensable gases, of a pipe for discharging said vapor and gas from the furnace, a substantially vertically arranged condenser connected to the outlet end of said pipe, means 5 for cooling said condenser, a receiver connected to the outlet of the condenser, means for maintaining the receiver in cooled condition, a powder outlet connected to said receiver and arranged to cause the powder 10 to rise and form a powder seal at the outlet end of the receiver, a gas discharge pipe connected to the receiver between the powder inlet and outlet, and a conveyer arranged in the receiver and adapted to force powder 15 along the receiver and into the powder outlet.

2. An apparatus as claimed in claim 1 in

which the conveyer is provided with a bucket wheel arranged opposite to the powder outlet and adapted to force the powder 20 through the outlet.

3. An apparatus as claimed in claim 1 in which the powder outlet is of elbow shape for causing the powder to travel in a tortuous path in leaving the apparatus. 25

In testimony whereof we have signed our names to this specification in the presence of two subscribing witnesses.
